UNITED STATES PATENT OFFICE.

CHARLES M. STROUD, OF HASTINGS, AND ALBERT J. MURDOCK, OF MINNEAPOLIS, MINNESOTA.

FIRE-POT FOR COOKING-STOVES.

SPECIFICATION forming part of Letters Patent No. 792,678, dated June 20, 1905.

Application filed March 7, 1904. Serial No. 196,838.

To all whom it may concern:

Be it known that we, CHARLES M. STROUD, residing at Hastings, in the county of Dakota, and ALBERT J. MURDOCK, residing at Minneapolis, in the county of Hennepin, State of Minnesota, citizens of the United States, have invented certain new and useful Improvements in Fire-Pots for Cooking-Stoves; and we do hereby declare the following to be a full, clear, and exact description of the invention, such as will enable others skilled in the art to which it appertains to make and use the same.

Our invention has for its object to provide an improved fire-pot for cooking-stoves; and to this end it consists of the novel devices and combinations of devices hereinafter described, and defined in the claims.

From practical experience we have found that coal will burn more economically and with less draft when confined in approximately cylindrical fire-pot chambers. At the same time it is a well-known fact that wood cannot be burned to advantage in chambers of such form, but, on the contrary, must have elongated chambers in which to lie when the same is to be burned in a fire-pot of the dimensions required in a cooking stove or range. Our invention provides a convertible fire-pot which is adapted to be quickly arranged either for the burning of coal or wood, and which will meet all of the requirements above noted.

The improved convertible fire-pot in its preferred form is illustrated in the accompanying drawings, wherein like characters indicate like parts throughout the several views.

Figure 1 is a view principally in side elevation, but with some parts broken away and with some parts sectioned, showing our improved fire-pot applied in working position to an ordinary cooking-stove. Fig. 2 is a detail in vertical section on the line $x^3 x^2$ of Fig. 1, some parts being broken away. Fig. 3 is an end elevation of the improved fire-pot removed from working position. Fig. 4 is a plan view of the said fire-pot, and Fig. 5 is a transverse vertical section on the line $x^5 x^5$ of Fig. 4.

Of the parts of a stove or range the numeral 1 indicates the body, the numeral 2 the

fire-pot chamber, the numeral 3 the grate, 50 and the numeral 4 the front griddles, which parts may be of the ordinary or any suitable construction.

The numeral 5 indicates the oblong integrally-formed body of the fire-pot, having 55 preferably notches 6 at its lower extremity. In form the chambers of the twin fire-pot are preferably tapered downward. On its inner intermediate surface the shell which forms the body of the twin fire-pot is formed with vertically-extended seats 7, in which loosely fit the ends of a removable bridge or pot-dividing partition 8. In horizontal section this bridge or partition 8 is double concave, and when placed in working position it completes 60 the formation of the two chambers of the fire-pot, the said chambers thus completed being approximately round in horizontal section and, as before stated, tapering down. The upper portion of the removable bridge or partition 8, however, lies materially below the upper extremities of the two fire-pot chambers, so as to leave the upper portions of the said chambers in communication at 9. The ends of the bridge or partition 8 taper down- 75 ward, so as to closely fit the seats 7 when dropped into its extreme lowered position. This tapering engagement also makes the removal of the bridge or partition an easy matter.

This improved fire-pot may be applied with- 80 in the combustion-chamber of the stove in a great many different ways; but preferably it is secured therein by means of fire-clay, tightly packed around the same and against the walls of the fire-pot chamber of the stove, so as to 85 cut off all draft through said chamber except through the chambers of said fire-pot. This manner of applying the fire-pot has the advantage that no close fits are required, since 90 the intervening space between the fire-pot and 90 the walls of the fire-pot chamber is all filled in with clay, and, furthermore, this method of application may be cheaply and quickly carried out.

When the bridge or partition 8 is placed in 95 working position, two distinct fire-pot chambers are afforded, and the fire in each may be varied without varying the fire in the other,

and at the same time when a very heavy fire is desired and the two pots are completely filled with coal the two fires may run completely together by the burning coal contained within the space 9. However, unless a heavy draft is employed the coal in the space 9 will not be burned to any great extent, but will be held in reserve and will be fed down into the fire-pot chambers as the coal burns away. Hence from several points of view the communicating space 9 between the two fire-pots is important.

If desired, hard coal can be burned in one chamber of the fire-pot and soft coal in the other, or coal may be burned in one chamber and short pieces or blocks of wood in the other. Again, fire may be maintained only in one chamber when a light fire is desired.

When the bridge or partition 8 is removed, the two fire-pots are, as already stated, thrown into one, which is then perfectly adapted to the burning of wood. This convertible fire-pot therefore adapts the stove to be used to burn wood in the summer-time and coal in the winter-time.

By actual experience we have found that by use of the fire-pot above described placed within the fire-pot chamber of a standard cooking-stove as a substitute for the ordinary grates or rectangular fire-pots designed to burn coal a very much greater heat is obtainable with a smaller quantity of fuel and, furthermore, that the stove will burn well under less draft and that a great saving of fuel is effected. We have also found that the fire will require less poking, will retain a fire longer when the stove is tightly closed, and will fire up more quickly when the draft is turned on. Since the fire is concentrated directly at points under the openings which are normally closed by the griddles 4, a very great heat is available at these openings for cooking purposes. A pot or other cooking utensil set into one of the griddle-holes will 45 be located directly over one of the fire-pot

chambers, and hence will be subject to the most intense heat available.

From the foregoing description and statements made it will be understood that the device described is capable of modification within the scope of our invention as herein set forth and claimed.

What we claim, and desire to secure by Letters Patent of the United States, is as follows:

1. A twin fire-pot having an integrally-formed body, and having a removable bridge or partition fitting between the extremities thereof, the top of which bridge terminates materially below the top of said body, substantially as described.

2. A twin fire-pot comprising a body having approximately semicylindrical extremities, and having a centrally-located double concave bridge or partition coöperating with the said body to form two fire-pot chambers 65 that are approximately round in horizontal section, substantially as described.

3. A fire-pot body having removably seated, between its extremities, a bridge or partition, the top of which terminates materially below the top of said body, substantially as described.

4. A twin fire-pot comprising the integrally-cast body 5, formed with internal seats 7, said body tapering downward, and the detachable bridge or partition 8 fitting said seats 7 at its ends, and terminating at its upper edge below the top of the said body 5, and which bridge or partition is concave on both sides, and coöperates with the end portions of said body 5 to form two chambers that are approximately round in horizontal section, substantially as described.

In testimony whereof we affix our signatures in presence of two witnesses.

CHARLES M. STROUD.
ALBERT J. MURDOCK.
